[57] CLAIM

The ornamental design for an automobile tire, as shown and described.

DESCRIPTION

FIG. 1 is a perspective view of an automobile tire showing our new design, it being understood that the tread pattern is repeated throughout the circumference of the tire;

FIG. 2 is an end elevational view thereof;
FIG. 3 is a side elevational view of the side shown, the opposite side being a mirror image thereof; and
FIG. 4 is a cross-sectional view thereof, taken about line 4—4 of FIG. 2.

FIG. 1

FIG. 2

FIG. 3

FIG. 4
